US0D1058396S

(12) **United States Design Patent** (10) **Patent No.:** **US D1,058,396 S**
(45) **Date of Patent:** **** Jan. 21, 2025**

(54) **TRACKING DEVICE**

(71) Applicant: **JIANGXI KINGTRON TECHNOLOGY CO., LTD.**, Ganzhou (CN)

(72) Inventor: **Zhibo Wu**, Hubei (CN)

(73) Assignee: **JIANGXI KINGTRON TECHNOLOGY CO., LTD.**, Ganzhou (CN)

(**) Term: **15 Years**

(21) Appl. No.: **29/935,449**

(22) Filed: **Apr. 2, 2024**

(51) **LOC (15) Cl.** **10-04**

(52) **U.S. Cl.**

USPC **D10/70**

(57) **CLAIM**

The ornamental design for a tracking device as shown and described.

DESCRIPTION

FIG. 1 is a front, right side, top perspective view of a tracking device showing the claimed design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a rear, left side, bottom perspective view thereof. The broken lines depict portions of the tracking device in which the design is embodied that form no part of the claimed design.

1 Claim, 6 Drawing Sheets
